MECHANISM FOR VARYING THE TENSION
OF NORMALIZING SPRINGS OF TYPE-
WRITERS OR LIKE MACHINESJohn F. Kloski, Hartford, Conn., assignor to Royal
Typewriter Company, Inc., New York, N. Y., a
corporation of New York

Application August 16, 1949, Serial No. 110,534

15 Claims. (Cl. 197—33)

1

This invention relates to mechanism for varying the tension of normalizing springs of typewriter or like machines, and more particularly to mechanism for varying the tension of springs, the normalizing force of which has to be overcome by finger pressure applied to the space bar or keys of such machines, especially power operated typewriters.

The prior art is replete with devices for adjusting the tension of springs which function to return key levers of typewriter or like machines to normal or non-depressed positions. The principal broad object of the present invention is to provide key or the like normalizing spring adjusting mechanism which is of novel and improved construction and arrangement, and which enables fine or close adjustments to be made without the use of intricate or expensive parts, or the maintenance of uneconomically close tolerances.

In some power operated typewriter constructions, a key is depressed to move an intermediate drive-transmitting element into engagement with a continuously operating driving member, whereupon the drive transmitting element is actuated so as in turn, to actuate an associated typewriter instrumentality, e. g., a type bar, carriage feeding or back spacing mechanism, or any of the other well known typewriter mechanisms. In some such machines, each key lever is provided with a normalizing or returning spring; and the associated intermediate or drive-transmitting mechanism is provided with one or more additional normalizing springs for the appropriate parts. The arrangement is such that all of the normalizing springs associated with a particular mechanism group, for example, a typing key, type bar, actuating mechanism, and intervening connections, resist depression of the key. In accordance with the present invention, the total normalizing force of a plurality of springs tending to resist depression of a single key is made accurately adjustable by providing mechanism for variably tensioning one or more but less than all of the springs associated with each key lever or other manually operable part. One of the objects of the invention is to provide a novel, simple, and efficient mechanism for effecting such adjustments.

A further object of the invention is to provide novel and improved mechanism for adjusting the position of the normalizing spring anchor of a typewriter or like machine.

Other objects will become apparent from a reading of the following description, the appended claims and the accompanying drawings, in which:

2

Figure 1 is a view, partly in elevation and partly in vertical section, fore-and-aft of a typewriter embodying the invention, showing only some of the conventional or standard typewriter parts in order to illustrate the application of mechanism embodying the invention to a typewriter construction;

Figure 2 is a fragmentary fore-and-aft sectional view of the spring tension adjusting mechanism shown in Figure 1, drawn on an enlarged scale, the section being on the line 2—2 of Figure 3;

Figure 3 is a horizontal sectional view on the line 3—3 of Figure 1, drawn on an enlarged scale, with some parts omitted;

Figure 4 is a detail perspective view of an indicator sector included in the construction disclosed in Figures 1, 2, and 3;

Figure 5 is a vertical fore-and-aft sectional view similar to Figure 2 but showing a modified construction; and

Figure 6 is a view also similar to Figure 2 but showing a further modified construction.

The invention may be embodied in typewriters or like machine of various kinds. For the purposes of illustration, the invention is shown as being embodied in an office type typewriter having, except for the power mechanism and spring tension adjusting mechanism to be described, many features in common with the well known Royal Standard typewriter. The drawings show only enough of the standard or known typewriter construction to assist in illustrating the manner in which mechanism embodying the invention may be coordinated with other parts of a typewriter construction.

The known construction illustrated includes a main frame A on which a carriage B equipped with a platen C is mounted for letter spacing and return movements by means of a top rail 1 secured to the carriage, and rolling upon balls 2, which in turn are adapted to roll on a frame-mounted bottom rail or track 3.

The carriage may be driven toward the left, that is, in the letter-spacing direction, by any suitable mechanism, for example, by a spring barrel and draw band of known or suitable construction (not shown), under the control of suitable escapement mechanism operated, for example, as disclosed in the copending application of Henry J. Hart, Serial No. 98,738, filed June 13, 1949 (now Patent No. 2,563,722, dated August 7, 1951).

Returning of the carriage toward the right may be effected by power controlled from the typewriter keyboard, for example, by mechanism of

the kind disclosed in the copending application of Henry J. Hart, Serial No. 21,476, filed April 16, 1948.

The machine is provided with the usual complement of type bars, one of which is shown at 4 in Figure 1 as being pivoted at 5 on a support or segment 6 equipped with a type bar abutment or banking ring 7. Normally the type bar 4 is in the position shown in Figure 1 with the type head resting upon a cushion 8. The type bar segment 6 may be shifted to upper and lower case positions by any suitable mechanism, for example, by power-operated mechanism of the kind shown in the copending application of William H. Kupper, Serial No. 133,322, filed December 16, 1949.

Power for operating the type bars or other instrumentalities is supplied by an electric motor (not shown), which drives an actuating mechanism generally designated D. The mechanism D is generally similar to mechanism described and claimed in copending application Serial No. 98,738 referred to above, and is similar to but embodies improvements in mechanism disclosed in the copending application of William H. Kupper, Serial No. 6,066, filed February 3, 1948. It includes a continuously operating driving member and controllable driving connections, which normally are inoperative or ineffective, but which may be conditioned by the operator to effect operative driving connection between the continuously moving driving member and the instrumentalities to be operated. The driver is constituted by a continuously rotating element, more particularly a toothed snatch roll or bar 9, which may be of known form, and which is adapted to be driven in the direction of the arrow a in Figure 1.

The mechanism for transmitting drive from the driver 9 to each of the type bars 4 includes an actuator 10 which extends fore-and-aft of the typewriter and above the member 9. The actuator 10 is pivoted as at 11 to a lever 12 at a point offset relatively to the pivotal mounting 13 of the lever on a fixed frame cross bar 14. The actuator has a forwardly extending part 15 projecting under an abutment or guide plate 16 mounted by screws 17 on the frame A to extend parallel to the snatch roll 9. The downwardly extending part 15a of the actuator 10 projects through a slot (not shown) in the lower guide plate 18 which is secured to the frame by the screws 17. The actuator part 15a is cooperable with an adjustable knock-off plate or member 19 for a purpose to be described hereinafter.

A normalizing spring 20 is interposed between the front end of the actuator 10 and an anchor plate 21 secured by screws 22 to a fixed cross bar 23. The spring 20 normally maintains the actuator 10 in the position shown in Figure 1 with the front end 15 of the actuator immediately below the upper guide plate 16.

The guide plates 16 and 18 and the spring anchor 21 extend across the front of the machine, the guide plates being cooperable with other actuators and associated parts similar to the actuator 10 and its associated parts, and the anchor 21 serving to anchor springs connected to the other actuators and corresponding to the spring 20 shown in Figures 1 and 2.

A link 24, pivotally connected to the lever 12 and the heel of the type bar 4 at 25 and 26 respectively, causes the type bar to be driven clockwise to printing position when the lever 12 is rocked counterclockwise in the manner described below.

In order to apply a power impulse to the type bar 4, the actuator 10 is operatively but indirectly connected to the driving member 9, the actuator itself never engaging the driving member. Mechanism for bringing about the operative connection of the actuator element 10 to the member 9 includes an interponent pawl 27, pivoted as at 28 on the actuator. A spring 29, anchored to the actuator 10 and connected to the pawl 27, biases or urges the latter to rock clockwise so as to move its nose 27a into engagement with the snatch roll 9. Normally, the pawl is maintained out of engagement with the snatch roll by the restraining action of a control element or trigger 30 which is pivoted as at 31 on the actuator 10. In the normal position of the trigger, its rear end 32 engages a holding surface 33 on the pawl so as to prevent the spring 29 from rocking the pawl element 27 into transient drive-transmitting engagement or connection with the driving member 9. The pawl 27 is formed with an inclined resetter cam face 34 which is located just below the holding surface 33, and which is acted upon by the trigger for rocking the pawl counterclockwise, and thus resetting it in normal, inoperative position.

Operator controlled means including a manually operable key 35 pivoted at 36 on the frame A is provided for bringing about operative driving connection between the driver 9 and the actuator 10. The key 35 has an upward projection 37 disposed behind an arm 38 of an operating lever 39, pivoted as at 40 on the frame-mounted cross bar 23. The lever 39 has another arm 41 on which a limber dog or flipper 42 is pivoted at 43. A spring 44 urges the limber dog 42 to rock clockwise to yieldably retain it in its normal position of rest against a limit stop 45 and above an ear 46 on the actuator 10. The dog 42 can swing counterclockwise from the position shown in Figure 1, but cannot move clockwise from this position.

A normalizing or returning spring 47 is connected at its lower end to the intermediate lever 39, and at its upper end to a spring anchor 48 secured to the cross bar 23 by the screw 22. The anchor 48 extends transversely of the machine so as to provide an anchorage for springs corresponding to the spring 47 and connected to other intermediate levers such as the lever 39 shown in Figure 1. The spring 47 normally holds the intermediate lever 39 in the position shown in Figure 1, so that the lower end of the flipper 42 is positioned just above the ear 46 on the actuator 10.

The key lever 35 is normally held in elevated position by a normalizing spring 49, the lower end of which is connected to an ear 50 on the key lever, and the upper end of which is connected in an aperture 51 formed in an anchor plate 52 which may be adjusted to vary the tensioning of the spring 49 in a manner to be described hereinafter.

In operation, when the key 35 is depressed, the lever 39 is rocked clockwise to cause the flipper 42 to push the actuator 10 downwardly to an initial extent sufficient to bring the trigger 30 into engagement with the abutment 18. This causes the trigger to be rocked clockwise about its pivot 31, so as to release the pawl 27, which is then moved by the spring 29 into engagement with the snatch roll 9. The snatch roll then drives the pawl 27 and actuator 10 as a unit so as to rock the lever 12 and operate the link 24 and type bar 4. When the pawl 27 is cast off

from engagement with the snatch roll 9, the spring 20 lifts the actuator 10 to bring the trigger 30 into engagement with the upper, trigger-resetting abutment 16. This causes the trigger 30 to be rocked counterclockwise, so as to move its end 32 against the resetting cam face 34 of the pawl 27, thereby restoring the latter to its inactive position. The parts will then be returned to their normal positions by the coaction of the springs 20 and 47 and a spring 53 interposed between the rear of the frame A and a link 54 connected to the lever 12.

Means of the kind disclosed in the copending application of Henry J. Hart, Serial No. 102,634, are provided for adjusting or varying the amount of driving impulse delivered to the individual pawl 27 by the snatch roll 9. The individual variation or adjustment is effected by variably limiting the extent to which the actuator pawl nose 27^a enters a tooth interspace on the snatch roll 9 under the urge of the spring 29 when the restraint of the trigger 30 on the pawl 27 is discontinued. In the form shown, the actuator 10 is provided with a downwardly extending stop element or finger 55 which is disposed in front of and normally out of contact with a downwardly extending stop part, heel, or finger 56 on the pawl 27. When the pawl 27 is rocked clockwise by the spring 29 so as to move the pawl nose 27^a into a snatch roll tooth interspace, the pawl stop 55 moves toward the actuator stop 56, which may be so positioned as to be engaged by the stop 56 to arrest rocking of the pawl 27 before the tooth 27^a moves to the root of the snatch roll tooth interspace. By variably positioning one of the stops 55, 56, e. g., by bending the stop 55 towards or away from the stop 56, the extent to which the pawl tooth 27^a enters the tooth interspace can be varied. Consequently, the angle through which the snatch roll rotates while in contact with the pawl, which determines the amount of driving of the pawl 27 and actuator 10 by the snatch roll 9, can be varied. Any suitable means or construction may be provided for adjusting one of the stops 55, 56 relatively to the other. In the preferred construction the stop 55 is formed integrally with the actuator 10 so as to be bendable toward or away from the stop 56.

In typewriters or like machines in which all or some of the instrumentalities to be operated, e. g., escapement mechanism, carriage return mechanism, tabulating mechanism, as well as typing mechanism, are operated by power, it is desirable to provide means for varying collectively the driving impulse transmitted to the several actuator pawls corresponding to the pawl 27 and associated with the other type bars and mechanisms referred to. This may be accomplished by providing the knock-off bar 19 extending under the front ends of all of the actuators corresponding to the actuator 10 shown in Figure 1. Any suitable means (not shown) may be provided for adjustably tilting or otherwise variably positioning the knock-off bar 19 so that it will be engaged by the lower ends of the actuators to control the timing of disengagement of the associated actuator pawls from the snatch roll.

In order to avoid congestion of the parts at the front of the machine, principally the key levers and space bar, the key levers 35 are mounted, some on the upper pivot rod 36 and others on a lower pivot 51 as shown in Figure 1, the arrangement being described more fully in

the copending application of William H. Kupper, Serial No. 6,066, previously referred to. The keys on some of the key levers 35 are located more distantly from the associated pivots than the keys on other of the key levers. To compensate for the differences in leverage so as to provide substantial uniformity of "touch" or resistance to key depression, the key lever returning springs 49 may have different characteristics so as to exert different key raising or normalizing efforts. Thus, the springs connected to the key levers having keys on the first or lower bank of keys may be somewhat stronger than the springs 49 for returning or normalizing the key levers having keys in the second bank. It will be seen that all of the springs associated with each key lever 35, namely, the actuator normalizing spring 20, the intermediate lever normalizing spring 47, and the key lever normalizing spring 49, resist depression of the key lever. In accordance with the present invention, the touch or force needed to be exerted on a key for actuating the associated mechanism is regulated by varying or adjusting the tension of less than all of the associated three springs. In the form shown in Figures 1 to 4, the touch is regulated by adjusting or varying the tension of only one of the three springs, specifically, the spring 49 connected between the key lever and the anchor 52.

Such adjustment is effected by changing the position of the anchor 52 by mechanism now to be described. The anchor 52 is in the form of a plate extending transversely of the machine and having a part 58 wrapped around a rod 59 and secured to the rod by pins 58^a. The rod 59 has pivot end portions 60 which extend through and are pivoted in openings in bearing plates 61 secured by screws 62 to brackets 63 mounted on the main frame A. The brackets 63 are formed with open-end slots 64 which receive the pivot parts 60 of the rod 59. Because of the slots 64 being open at their front ends, the anchor assembly 52-59 may readily be dismounted from the brackets 63 by removing the screws 62 so as to free the plates 61. The brackets 63 also support the knock-off bar 19 and the cross bar 23 previously referred to.

When the anchor 52 is rocked clockwise as viewed in Figures 1 and 2, the springs 49 are stretched or additionally tensioned so as to require a heavier or increased touch for operating the key lever 35 and the associated intermediate lever 39 and actuator 10. Conversely, when the anchor 52 is rocked counterclockwise, the spring 49 is permitted to contract so as to reduce its tension, thereby providing for operation with a lighter touch. Close control of the variation in the touch required is made possible by varying the tension of only one of the springs opposing depression of the key lever 35, the arrangement being such that considerable movement of the plate 52 is required to produce an appreciable or noticeable change in the touch characteristics. Adjustment of only one of the three springs 20, 47, and 49, while leaving the tension of the other two of the springs unchanged, avoids undesirable jumpy or erratic changes in the touch regulation.

Improved mechanism is provided for rocking the spring anchor 52. In the form shown in Figures 1 to 4, a U-shaped bracket 65 is secured to the front frame cover 66 by screws, one of which is shown at 67. The upper and lower legs of the bracket provide bearings for a shaft 68

formed at its lower end with a screw or worm thread 69. A shoulder 70 on the shaft 68 abuts the upper leg of the bracket 65 to hold the shaft 68 against upward movement, and a knob 71 secured to the top of the shaft 68 by set screws 71^a holds the shaft against downward movement. A worm wheel sector 72 secured to the anchor rod 59 by a set screw 73 is formed with a series of teeth meshing with the worm teeth 69, so that, upon rotation of the shaft 68 by the knob 71, the sector 72 and the anchor 52 will be rocked about the axis of the pivots 60 so as to vary the tension of the spring 49.

In order to limit rocking of the anchor 52 and to prevent over-or under-stressing of the springs 49, the sector 72 is formed with stop portions 74 and 75 (Figure 2) at the respective ends of the series of sector teeth on the same arc and diameter as the crests of the teeth. When the parts are in a limit position, as shown in Figure 2, an upper thread convolution of the worm 69 will bear against the stop portion 75 so as to prevent further rotation of the knob 71 and rocking of the anchor 52, thus preventing over-stressing of the springs 49. Similarly, when the sector 72 is rocked counterclockwise to its opposite limit position, a lower thread convolution on the worm 69 will bear against the other stop portion 74 so as to prevent further rocking of the anchor 52. The stop portions 74 and 75 serve not only to limit the adjusting of the springs 49, but also to prevent the worm 69 and sector teeth from being unmeshed.

In order that the operator may be informed as to the touch regulation, an indicator sector 76 is secured to the spring anchor rod 59 by means of a set screw 77, and is provided peripherally with scale marks 78 viewable through a window or opening 79 above which is a pointer 80, adapted to register with a scale marking 78 for indicating the particular setting or adjustment of the tension of the returning springs 49.

In the modification shown in Figure 5, the key mechanism 35, 36, intermediate lever 39, and actuating mechanism including the actuator 10 are the same as are shown in Figure 1, and are shown only partially in Figure 5. The mechanism shown in Figure 5 differs from that previously described in that the key lever normalizing spring 49 is under constant tension, whereas the actuator normalizing spring 20 and the intermediate lever normalizing spring 47 are arranged to be adjusted. The Figure 5 construction, however, is similar to the construction shown in Figures 1 to 3, in that less than all of the springs which resist the depression of the associated key are adjustable, so that a smooth, dependable adjustment or regulation of the touch is obtainable. As shown in Figure 5, an adjustable spring anchor 81 is provided with ears, one, 82, of which is shown, pivoted on a rod 83 carried by ears, one of which is shown at 84 extending forwardly from the frame cross bar 23. The rod 83 serves not only as a pivot for the anchor 81, but also as an upper anchorage for the non-adjustable key lever normalizing springs 49. The anchor 81 is formed with holes 85 for attachment of the upper ends of the springs 20 and 47.

Mechanism for rocking the anchor 81 includes a bracket 86 secured by a screw 87 to the front mask panel 66, and an internally threaded sleeve 88 extending through which is an adjusting screw 89. The parts are so mounted that the screw axis extends upwardly and forwardly with respect to the machine. A clevis 90 is mounted on the

lower end of the screw 89 by a connection comprising a groove 91 in the screw, and a pin 92 in the clevis extending tangentially through the groove so as to permit relative rotation of the screw and clevis, but so as to constrain the clevis to partake of the translatory movement of the screw. A coupling pin 93 extending transversely through the clevis 90 is encompassed by the wrapped end 94 of a leaf 95 riveted as at 96 to the anchor 81.

A knob 97 is secured to the upper end of the screw 89 by a set screw 98, and is formed with a frusto-conical circumferential part 99 provided with scale markings 100 which may be read in connection with a fixed pointer 101 secured to the front mask panel 66 by the screw 87. By rotating the knob 97, the screw is caused to move upwardly or downwardly so as to rock the anchor 81 about its pivot 83, thereby increasing or decreasing the tension of the normalizing springs 20 and 47. The inclination of the frusto-conical scale portion 99 facilitates observation or reading of the scale-indicated adjustment of the spring tension, and hence facilitates setting the touch control mechanism.

The modified construction shown in Figure 6 is adapted for use in connection with key mechanism, intermediate lever mechanism, and actuator mechanism of the kind disclosed in Figure 1, and only a part of the actuator 10 is shown. In this embodiment of the invention, only one of the three normalizing springs, namely, the actuator normalizing spring 20, is adjustable. A bracket 102 secured to the frame cross bar 23 is formed with a fixed front anchor 103 for the key lever normalizing springs 49, and with a fixed rear anchor portion 104 for the intermediate lever normalizing springs 47. The bracket 102 has an upper part 105 secured to the front frame panel 66 by a screw 106. Ears, one of which is shown at 107, on the bracket 102, support a pivot rod 108 on which are pivoted ears, one of which is shown at 109, extending downwardly from an adjustable anchor 110 for the actuator springs 20. The tensioning of the springs 20 is adjusted by rocking the anchor 110 by mechanism including an ear 111 on the bracket 102, on which is mounted a pivot screw 112 for a manually adjustable arm or lever 113. A link 114 is pivoted at 115 to the arm 113, and is pivoted at 116 to an ear 117 on an extension 118 of the anchor 110. Rocking of the arm 113 about its pivot 112 acts through the link 114 and extension 118 to rock the anchor 110 so as to increase or decrease the tension of the springs 20, according to the direction in which the arm 113 is rocked. In order that the arm 113 will be retained releasably in a selected or set position of adjustment, it is formed with a plurality of flat chordal parts 119 contactable with a leaf spring 120 secured to the bracket upper part 105 by screws 121. An indicator segment 122 secured to the bracket upper part 105 and the front mask panel 66 by the screw 106 is formed with three raised indicator or guide parts 123 for assisting the operator in determining the set or adjusted position of the arm 113, and hence the tensioning of the springs 20 and the touch regulation.

Preferred embodiments of touch control mechanism constructed in accordance with the invention have been described as applied to the typing keys of a typewriter. Mechanism embodying the invention, however, may be and is intended to be used in connection with the other keys of typewriter or like machines, such as the

space bar 124, shift key 125, and back spacing key 126, all of which are indicated in Figure 1. It may also be applied in connection with such other auxiliary or service keys as the shift lock key, tabular key, margin release key, and the carriage return key of a power operated typewriter.

Because of the dependable and close regulation of the touch which can be accomplished with mechanism embodying the present invention, such mechanism has particular utility in connection with power operated typewriters constructed for operation with a touch lighter than normally is required in operating a conventional manually operated machine. When an experienced operator, accustomed to using a manually operated typewriter, first uses a power operated machine, the operator may find the touch unsatisfactorily or unpleasingly light. During transition from manual machine operation to powered machine operation, it may be desirable to set the touch regulating mechanism so as to require a key pressure not too much less than is required in the use of a manually operated machine, and thereafter to decrease the pressure from time to time until full advantage of the light touch characteristics of a power operated typewriter can be realized to the satisfaction of the operator. For this reason, and because of the very close and reliable key pressure regulation obtainable with mechanism embodying the invention, the invention is particularly, although not exclusively, adapted for use in power operated typewriters.

The constructions shown and described embody the invention in preferred forms, but it is intended that the disclosure be illustrative rather than definitive, the invention being defined in the appended claims.

I claim:

1. In a power operated typewriter or like machine, a power driven member; instrumentalities to be operated by said member; actuators respectively connected to said instrumentalities; a spring anchor; a set of normalizing springs connected to said anchor and respectively connected to said actuators for yieldably holding said actuators disconnected from said member; means including key levers for moving said actuators selectively against the urge of the associated normalizing springs into engagement with said member; another spring anchor; a set of normalizing springs connected to said other spring anchor and respectively connected to said key levers; means mounting one of said anchors pivotally to rock about an axis offset from the points of connection of the associated springs thereto; a worm wheel sector connected to the pivotally mounted anchor; and a manually rotatable worm cooperable with said worm wheel sector for rocking the pivotally mounted anchor to vary the normal tensioning of the springs connected thereto.

2. In a power operated typewriter or like machine, a power driven member; instrumentalities to be operated by said member; actuators respectively connected to said instrumentalities; a spring anchor; a set of normalizing springs connected to said anchor and respectively connected to said actuators for yieldably holding said actuators disconnected from said member; means including key levers for moving said actuators selectively against the urge of the associated normalizing springs into engagement with said member; another spring anchor; a set of nor-

malizing springs connected to said other spring anchor and respectively connected to said key levers; means mounting one of said anchors pivotally to rock about an axis offset from the points of connection of the associated springs thereto; a worm wheel sector connected to the pivotally mounted anchor and having a series of teeth and stop portions respectively at the ends of the series and on the same arc and diameter as the crests of the teeth; and a manually operable worm meshing with said sector teeth and being cooperable therewith for rocking the pivotally mounted anchor to vary the tensioning of the springs connected thereto, said stop portions being engageable by the worm teeth for determining limits of rocking of the pivotally mounted anchor.

3. In a power operated typewriter or like machine, a power driven member; instrumentalities to be operated by said member; actuators respectively connected to said instrumentalities; a spring anchor; a set of normalizing springs connected to said anchor and respectively connected to said actuators for yieldably holding said actuators disconnected from said member; means including key levers for moving said actuators selectively against the urge of the associated normalizing springs into engagement with said member; another spring anchor; a set of normalizing springs connected to said other spring anchor and respectively connected to said key levers; means mounting one of said anchors pivotally to rock about an axis offset from the points of connection of the associated springs thereto; a fixed, internally threaded sleeve; a manually rotatable screw having threaded engagement with said sleeve; and means connecting said screw to the pivotally mounted anchor for rocking the latter in consequence of translatory movement of the screw caused by manual rotation thereof.

4. In a power operated typewriter or like machine, a power driven member; instrumentalities to be operated by said member; actuators respectively connected to said instrumentalities; a spring anchor; a set of normalizing springs connected to said anchor and respectively connected to said actuators for yieldably holding said actuators disconnected from said member; means including key levers for moving said actuators selectively against the urge of the associated normalizing springs into engagement with said member; another spring anchor; a set of normalizing springs connected to said other spring anchor and respectively connected to said key levers; means mounting one of said anchors pivotally to rock about an axis offset from the points of connection of the associated springs thereto; a pivotally mounted, manually operable adjusting arm connected to the pivotally mounted anchor for rocking the latter to vary the normal tensioning of the springs connected thereto, said arm being formed with a plurality of flat surfaces substantially chordal with respect to the arm pivot axis; and a leaf spring adapted to bear against any one of said surfaces, according to the position of said arm, for yieldably holding the latter in set adjusting position.

5. In a power operated typewriter or like machine, a power driven member; instrumentalities to be operated by said member; actuators respectively connected to said instrumentalities; a spring anchor; a set of normalizing springs connected to said anchor and respectively connected to said actuators for yieldably holding

said actuators disconnected from said member; means including key levers for moving said actuators selectively against the urge of the associated normalizing springs into engagement with said member; another spring anchor; a set of normalizing springs connected to said other spring anchor and respectively connected to said key levers; means mounting one of said anchors pivotally to rock about an axis offset from the points of connection of the associated springs thereto; a pivotally mounted manually operable adjusting arm; means including a link connecting said arm to the pivotally mounted anchor for rocking the latter when the adjusting arm is rocked to vary the tensioning of the springs connected to the pivotally mounted anchor, said arm being formed with a plurality of flat surfaces substantially chordal with respect to the arm pivot axis; and a leaf spring adapted to bear against any one of said surfaces, according to the position of said arm, for yieldably holding the latter in set adjusting position.

6. In a power operated typewriter or like machine, a power driven member; instrumentalities to be operated by said member; actuators respectively connected to said instrumentalities; a first spring anchor; a set of normalizing springs connected to said first spring anchor and respectively connected to said actuators for yieldably holding said actuators disconnected from said member; means including key levers for moving said actuators selectively against the urge of the associated normalizing springs into engagement with said member; another spring anchor; a set of normalizing springs connected to said other spring anchor and respectively connected to said key levers; means mounting said first spring anchor pivotally to rock about an axis offset from the points of connection of the associated springs thereto; and manually operable means for rocking said first spring anchor to vary the normal tensioning of the springs connected thereto.

7. A construction as set forth in claim 1, in which the springs connected to the key levers are connected to the pivotally mounted anchor.

8. A construction as set forth in claim 3, in which the springs connected to the actuators are connected to the pivotally mounted anchor.

9. A construction as set forth in claim 4, in which the springs connected to the actuators are connected to the pivotally mounted anchor.

10. In a power operated typewriter or like machine, a power driven member; instrumentalities to be operated by said member; actuators respectively connected to said instrumentalities; a first spring anchor; a set of normalizing springs connected to said anchor and respectively connected to said actuators for yieldably holding said actuators disconnected from said member; key levers; intermediate levers respectively interposed between said key levers and said actuators and being responsive to key lever depression for moving said actuators selectively against the urge of the associated normalizing springs into engagement with said member; another spring anchor; a set of normalizing springs connected to said other spring anchor and respectively connected to said key levers; a set of normalizing springs connected to said first spring anchor and respectively connected to said intermediate levers; means mounting one of said anchors pivotally to rock about an axis offset from the points of connection of the associated springs

thereto; and manually operable means for rocking the pivotally mounted anchor to vary the normal tensioning of the springs connected thereto.

5 11. A construction as set forth in claim 10, in which said first spring anchor is pivoted and said other spring anchor is at the pivotal axis of said first spring anchor.

10 12. A construction as set forth in claim 10, in which the springs connected to the intermediate levers and the actuators are connected to the pivotally mounted anchor.

15 13. In a power operated typewriter or like machine, a power driven member; instrumentalities to be operated by said member; actuators respectively connected to said instrumentalities; a spring anchor; a set of normalizing springs connected to said anchor and respectively connected to said actuators for yieldably holding said actuators disconnected from said member; key levers; intermediate levers respectively interposed between said key levers and said actuators and being responsive to key lever depression for moving said actuators selectively against the urge of the associated normalizing springs into engagement with said member; a second spring anchor; a set of normalizing springs connected to said second spring anchor and respectively connected to said key levers; a third spring anchor; a set of normalizing springs connected to said third spring anchor and respectively connected to said intermediate levers; means mounting one of said anchors pivotally to rock about an axis offset from the points of connection of the associated springs thereto; and manually operable means for rocking the pivotally mounted anchor to vary the normal tensioning of the springs connected thereto.

20 14. In a typewriter or like machine, instrumentalities to be operated; means including key-operated levers for effecting operation of said instrumentalities selectively; a spring anchor; a set of springs connected to said anchor and respectively connected to said levers; means mounting said anchor pivotally to rock about an axis offset from the points of connection of said springs thereto; an internally threaded sleeve fixedly mounted on the machine adjacent the front thereof and with its axis being inclined forwardly and upwardly with respect to the machine; a screw having threaded engagement with said sleeve; means connecting the lower end of said screw to said anchor for rocking the latter in consequence of translation of said screw caused by rotation thereof; a manually rotatable knob secured to the upper end of said screw and having a scale-marked frusto-conical peripheral portion; and a fixed pointer cooperable with the scale markings for indicating the rotated position of said knob and screw and hence the rocked position of said anchor and the degree of tensioning of said springs.

25 15. In a typewriter or like machine, instrumentalities to be operated; means including key-operated levers for effecting operation of said instrumentalities selectively; a spring anchor; a set of springs connected to said anchor and respectively connected to said levers; means mounting said anchor pivotally to rock about an axis offset from the points of connection of said springs thereto; a pivotally mounted, manually operable adjusting arm connected to said anchor, said arm being formed with a plurality of flat surfaces substantially chordal with respect to the arm pivot axis; and a leaf spring adapted to bear

13

against any one of said surfaces, according to the position of said arm, for yieldably holding the latter in set adjusting position.

JOHN F. KLOSKI.
